LAMP HOLDER

Edward J. Petrick, Park Ridge, Ill.

Application April 22, 1955, Serial No. 35,643

Term of patent 14 years

(Cl. D48—20)

FIG. 1.

FIG. 2.

FIG. 3.

I claim:

The ornamental design for a lamp holder, as shown.
